INVENTOR

John Holtzman.

UNITED STATES PATENT OFFICE

JOHN HOLTZMAN, OF NEW YORK, N. Y.

RAZOR BLADE HOLDER

Application filed January 14, 1925. Serial No. 2,329.

This invention relates to a razor blade holder.

Fig. 1 represents a plan view of an exemplification of the razor blade holder; Fig. 2 shows a section of Fig. 1 on the line 2, 2; Fig. 3 is a section of Fig. 2 on the line 3, 3; Fig. 4 indicates an enlarged section of Fig. 1 on the line 4, 4; Fig. 5 represents an enlarged section of Fig. 1 on the line 5, 5; Fig. 6 shows an enlarged section of Fig. 1 on the line 6, 6.

Referring to Figs. 1 to 6 the razor blade holder is shown with a handle substantially oval in cross section, having the concaved bottom member 20, with the flat longitudinal flanges 21 at its sides, and the concaved top member 22 having the flat longitudinal flanges 23 at its sides which are somewhat separated from the flanges 21. The said top member 22 joins with said bottom member 20 at one end as indicated at 24. The end 28 of the member 20 opposite the end 24 is flat and somewhat reduced in width from the main portion thereof, and extends up on a level above said member 20, and has formed therewith the upwardly extending end flange 30. The end 28 constitutes a locking support.

Clearance recesses 31 and 32 are formed in the flanges 21 of the member 20. Locking pins 33 extend up from the member 20 and fulcrum supports 34 are formed with and extend up therefrom. A concaved hinged member 35 with the flat longitudinal flanges 36 is hinged to the bottom member 20, by means of the hinge pin 37. The flanges 36 of the hinged member 35 are normally separated from the flanges 21 of the member 20. Clearance recesses 38 are formed in the flanges 36 of the member 35. Fulcrum supports 41 extend down from the hinged member 35 and bear on the fulcrum supports 34 of the member 20. The swinging end of the member 35 has formed therewith the flat locking nose 42, which is adapted to bear on the locking support 28. A locking ring 43 is adapted to engage the locking nose 42 and the locking support 28 to lock the members 20 and 35 to each other.

A pair of guards 45 parallel to the longitudinal axis of the handle of the holder extend from the branch members 46, which

in turn extend from the shank members 47 and 48. An opening 49 tapering toward its top is formed in the shank member 47 and a similar tapered opening 50 is formed in the shank member 48. The fulcrum supports 34 and 43 extend into the openings 49 and 50 and enable the shank members with their guards to rock thereon.

To use the holder the hinged member 35 is swung up on the hinge pin 37 and the razor blade 55 having the edges 56 is located between the flanges 21 and 36 with its openings engaged by the locking pins 33. The member 35 is now swung down and the locking ring 43 is positioned to lock the nose 42 and support 28 to each other. With this disposition of the parts the razor blade 55 is securely clamped in position and the shanks 47 and 48 can rock on each pair of the fulcrum supports 34 and 42, and thereby rock the guards 45, to enable the edges 56 to contact with a sharpening or stropping device.

Various modifications may be made in the invention, the present exemplification is to be taken as illustrative and not limitative thereof.

Having described my invention what I desire to secure by Letters Patent and claim is:

1. In a razor blade holder the combination of a tubular shaped handle comprising a pair of members pivoted to each other with their longitudinal edges spaced from each other when said members are located in their closed position, said members having recesses, a pair of shanks fulcrumed within said members, a pair of branch members extending from the opposite sides of said shanks through the recesses of the handle, a guard connecting each pair of branch members, the members of the handle adapted to clamp a razor blade between them and between said guards and means to clamp the members of the handle to each other, said recesses limiting the rocking motion of said branch members with their guards.

2. In a razor blade holder, a device for holding a razor blade including a pair of holder members to clamp the razor blade at opposite sides, a guard within said device between said members and extending on both

sides thereof and presenting side bars in parallelism with the edges of the blade, and means to hold said guard for permissive relative rocking movement with regard to said device so that said guard is rocked by engagement with the strop to positions respectively at opposite sides of the edge of the blade.

3. In a razor blade holder, a device for holding a razor blade including a pair of holder members to clamp the razor blade at opposite sides, a guard within said device between said members and extending on both sides thereof and presenting side bars in parallelism with the edges of the blade, means to hold said guard for permissive relative rocking movement with regard to said device so that said guard is rocked by engagement with the strop to positions respectively at opposite sides of the edge of the blade, and a stop formed upon said device to limit said movement.

4. In a razor blade holder for use during stropping, a device for holding a razor blade including a pair of holder members to clamp the razor blade at opposite sides, a flat closed guard formed integrally and comprising side bars presented opposite the edges of a razor blade in said device and transverse bars adapted to be attached to said device for a relative movement with regard thereto, means to permit the rocking of said guard, and means upon said device to limit said movement.

5. In a razor blade stropper, the combination with a handle, comprising a pair of supporting members, of a shank supported between said members, branch members integrally connected and extending from opposite sides of the shank, a pair of guards parallel to and arranged coaxially with the longitudinal axis of the handle and integrally connected with said branch members, means to position a blade between the handle members and within the guards, said blade being held in position to be stropped and sharpened.

6. In a razor blade stropping device, a hollow handle having a blade holder connected rigidly therewith, said holder including elements to support the blade rigidly with regard to the handle for stropping, a rocking guard comprising a rigid rectangular frame having guard rods spaced from and parallel to the edges of the blade when in stropping position, a pivot pin on said holder substantially on the longitudinal axis of the blade and supporting one end of the guard, said guard entering said handle at its other end, and a journal for said guard located within said handle.

7. In a razor blade holder, a member comprising a handle and means for holding a double edged razor blade at opposite sides, with its edges free, a guard pivoted within said member and extending through aper-

tures on both sides thereof and presenting guide bars opposite the two edges of the blade, and pivoting devices to hold said guard for permissive rocking movement with regard to said device so that said guard is rockable upon engagement with the strop to positions respectively at opposite sides of the edge of the blade, said pivoting devices being located within the handle portion of said member.

8. In a razor blade holder, a pair of members each constituting an integral handle and blade holder element, one of said members having blade receiving and retaining lugs secured thereto and directed toward the other member, said members being pivoted together to move toward and from one another for placing a razor blade on and removing the same from said lugs, said members when together constituting a blade holder device for securing the razor blade in position, means to clamp said members together in operative position, and a guard pivotally mounted on one of said members on the side thereof adjacent the other member, said guard issuing from between said members.

Signed at the borough of Manhattan, city of New York, in the county of New York and State of New York, this 13th day of January, A. D. 1925.

JOHN HOLTZMAN.
